Patented Nov. 25, 1919.

FIG. 1.

FIG. 2.

Inventor
Lewis N. Rosencrans
by Herbert W. Jenner,
Attorney

UNITED STATES PATENT OFFICE.

LEWIS N. ROSECRANS, OF AMERICAN FALLS, IDAHO.

WRENCH.

1,322,623.

Specification of Letters Patent. Patented Nov. 25, 1919.

Application filed September 2, 1919. Serial No. 321,214.

To all whom it may concern:

Be it known that I, LEWIS N. ROSECRANS, a citizen of the United States, residing at American Falls, in the county of Power and 5 State of Idaho, have invented certain new and useful Improvements in Wrenches, of which the following is a specification.

This invention relates to wrenches for removing nuts from bolts; and it consists in 10 the novel construction and combination of the parts hereinafter fully described and claimed.

In the drawings, Figure 1 is a side view, partly in section, of a wrench constructed according to this invention. Fig. 2 is also a 15 side view, but shows the wrench turned one-quarter around from the position shown in Fig. 1.

A frame 2 is provided and has a push bar 20 or plate 3 at one end which is adapted to be pressed by the body of the operator. A longitudinal bearing 4 is provided at the other end of the frame, and 5 is a long tubular sleeve which is journaled in the bearing 4. 25 The sleeve has a bearing 6 on its free end portion which is arranged crosswise of its axis, and 7 is a beveled toothed wheel the hub 8 of which is journaled in the cross bearing 6. A socket 9 for engaging with 30 the nuts is connected to the hub 8, and this socket preferably has a rectangular shank 10 which is inserted in a similar hole in the wheel hub. Sockets of different size are 35 provided to suit different nuts, and they all have shanks 10 of the same size so that they can all be slid into engagement with the hole in the wheel hub 8.

The tubular sleeve 5 is revolved in the bearing 4 so that the socket 9 may be arranged to project from the frame 2 in any desired direction.

A shaft 12 is journaled in the tubular sleeve 5, and has a beveled toothed wheel 14 secured on one end portion of it, which gears 45 into the toothed wheel 7. A similar beveled toothed wheel 15 is secured on the other end portion of the shaft 12, and is arranged in an opening 16 in the frame 2.

A driving shaft 18 is journaled in bearings 50 19 on the frame, and is arranged crosswise of the shaft 12. Two beveled toothed wheels 20 and 21 are secured on the end portions of a hub or sleeve 24, which is slidable on the driving shaft, but which revolves with it. 55 The driving shaft preferably has a rectangu-

lar portion 25 which engages with a similar hole in the hub 24.

The two beveled wheels 20 and 21 are slid alternately into gear with the beveled toothed wheel 15, so that it may be revolved 60 in either direction without changing the direction of revolution of the driving shaft. The hub or sleeve 24 has a circumferential groove 26, and 27 is a forked arm or plate which engages with the groove 26. A guide 65 28 is provided on the frame 2, and 29 is a frame secured to the forked arm 27, and slidable in the guide 28 parallel to the driving shaft. An eccentric or cam 30 is arranged in the frame 29, and is secured on a shaft 31 which is journaled in the guide 28 and arranged crosswise of the driving shaft. The cam shaft 31 has a handle 32 secured on one end of it, for operating it and thereby sliding the two beveled wheels and their 75 hub back and forth on the driving shaft.

The driving shaft is provided with any approved means for revolving it, and 34 is a hand wheel secured on it for that purpose and provided with a handle 35. In order to 80 start a nut or to screw it up tightly, a lever 36 is also preferably provided. This lever has pawls 37 pivoted to it and adapted to engage with a ratchet toothed wheel 40 secured on the hub of wheel 7. When the pawls are 85 placed out of engagement with the ratchet toothed wheel, the driving shaft can be revolved rapidly by the hand wheel.

A wrench constructed according to this invention can be used on nuts in various parts 90 of machinery which are not freely accessible to wrenches as ordinarily constructed.

What I claim is:

1. In a wrench, a frame having a longitudinal bearing, a tubular sleeve journaled 95 in the said bearing, a revoluble nut socket carried by the said sleeve, a shaft journaled in the said sleeve, means for connecting the said shaft with the nut socket, a driving shaft journaled in the frame and arranged crosswise of the said shaft, and driving devices connecting the two said shafts.

2. In a wrench, a frame having a longitudinal bearing, a tubular sleeve journaled 100 in the said bearing, a revoluble nut socket carried by the said sleeve, a shaft journaled in the said sleeve, means for connecting the said shaft with the nut socket, a driving shaft journaled in the frame and arranged crosswise of the said shaft, and reversible 110

driving mechanism provided with beveled toothed wheels and operatively connecting the two said shafts.

3. In a wrench, a supporting frame having a longitudinal bearing, a tubular sleeve journaled in the said bearing and having a bearing arranged crosswise of its axis at its free end, a beveled toothed wheel journaled in the last said bearing, a nut socket operated by the said wheel, a shaft journaled in the tubular sleeve, a beveled toothed wheel secured on the said shaft and gearing into the said wheel, a driving shaft journaled in the said frame and arranged crosswise of the said shaft, and reversible driving mechanism provided with beveled toothed wheels and operatively connecting the two said shafts.

4. In a wrench, a supporting frame hav-

ing a longitudinal bearing, a tubular sleeve journaled in the said bearing and having a bearing arranged crosswise of its axis at its free end, a beveled toothed wheel journaled in the last said bearing, a nut socket operated by the said wheel, a ratchet toothed wheel secured to the said beveled toothed wheel, a lever pivoted concentric with the ratchet toothed wheel and provided with disengageable pawls for revolving it, a shaft journaled in the tubular sleeve, a beveled toothed wheel secured on the said shaft and gearing into the said beveled toothed wheel, a driving shaft journaled in the frame, and reversible driving mechanism connecting the two said shafts.

In testimony whereof I have affixed my signature.

LEWIS N. ROSECRANS.
